UNITED STATES PATENT OFFICE.

EARL ELWIN BERRY, OF BELOIT, WISCONSIN, ASSIGNOR TO BELOIT IRON WORKS, OF BELOIT, WISCONSIN.

FRICTION DRIVE FOR DRIERS.

Application filed December 15, 1923. Serial No. 680,822.

To all whom it may concern:

Be it known that I, EARL E. BERRY, a citizen of the United States, and a resident of the city of Beloit, in the county of Rock 5 and State of Wisconsin, have invented certain new and useful Improvements in a Friction Drive for Driers; and I hereby declare that the following is a full, clear, and exact description of the same, reference 10 being had to the accompanying drawings, and to the numerals of reference marked thereon, which form a part of this specification.

In paper web drying machines of the 15 Fourdrinier and similar types the drying cylinders or rolls are rotated by means of large intermeshing gears which not only set up vibrations and are noisy in operation but also cause considerable trouble in that the 20 gear teeth break off due to the excessive strain to which they are subjected. The breaking of gear teeth means, the replacement of the gear and a long delay for repairs during which time the entire machine 25 is out of use. The use of large driving gears also make it extremely difficult to obtain proper access to the drying cylinder bearings and journals.

To obviate the above mentioned defects in 30 driers for paper making machines and the like, this invention relates to an improved type of driving mechanisms for the steam drier cylinders of a paper making machine.

It is an object of this invention to provide 35 a web drying machine with friction drive mechanisms for the driers, thereby providing a construction of fewer parts and less expensive since the bearings and journals of the upper driers are not required.

It is also an object of the invention to 40 provide the drier cylinders of a paper drying machine with friction flanges to replace driving gears, said friction driving arrangement permitting easy removal of bunched 45 paper from between the cylinders in case the paper tears.

It is an important object of this invention 50 to provide a paper drying machine of improved construction wherein the drier cylinders are driven through friction flanges and wherein the lower drier cylinders are supported on roller or ball bearings, thereby affording a machine wherein vibrations and noise are greatly reduced.

Other and further important objects of 55 this invention will be apparent from the disclosures in the specification and accompanying drawings.

This invention (in a preferred form) is 60 illustrated in the drawings and hereinafter 60 more fully described.

On the drawings:

Figure 1 is a diagrammatic fragmentary side elevation of a paper drying machine.

Figure 2 is an enlarged fragmentary side 65 elevation of a portion of the machine illustrating part of the framework.

Figure 3 is a fragmentary detail view taken on line 3—3 of Figure 2.

Figure 4 is an enlarged vertical detail 70 view through the roller bearing support at the front side of one of the drier cylinder supports (line 4—4, Figure 2) showing the housing in section.

Figure 5 is a detail sectional view through 75 the support for one of the driving drier cylinders (line 5—5, Figure 1) with the motor and parts omitted.

Figure 6 is a view taken on line 6—6 of 80 Figure 4.

As shown on the drawings:

Figure 1 illustrates a diagrammatic side elevation of the drier unit of a paper drying machine of the Fourdrinier type and comprising a plurality of lower drier cylinders 85 1, driving cylinders 2, and upper cylinders 3. A plurality of guide rolls 4 are provided for supporting drier felt conveyors 5 which conduct a web to be dried through the machine in contact with the drier cylinders which are 90 steam heated.

The upper tier of drier cylinders 3 are positioned to rest on the lower tier of drier cylinders 1 and 2 as illustrated in Figures 1 and 2. Each of the cylinders 1, 2 and 3 95 has rigidly bolted or otherwise secured to one end thereof a ring driving flange 6 (Figure 3) each having a beveled portion 7. The driving flanges frictionally contact one another and thus impart a rotary motion to 100 the drier cylinders. The cylinders 2 are the driving cylinders and each is provided at one end with a shaft or trunnion 8 having a roller 9 fixed or formed thereon intermediate the ends thereof and adapted to run on bearing rollers within a bearing housing 10 similar to the arrangement illustrated in Figure 4. Fixed on the outer end of each 105

of the driving trunnions 8 is a gear which meshes with a driving gear mounted on the end of the shaft of a driving motor 11.

A drive from a motor 11 is thus transmitted through the meshing gears to the trunnion 8 and the respective driving cylinder 2 the driving flange 6 of which being in frictional contact with the flanges 6 of two of the upper tier cylinders 3 causes rotation of said upper cylinders which in turn serve to transmit the drive to the remaining cylinders through the friction flanges. All of the drier cylinders are thus frictionally driven and act to dry a web conducted therebetween by the drier-felts.

Each of the lower tier drier cylinders 1 is provided with a trunnion 12 having a supporting roller 13 mounted or formed thereon and resting on a pair of bearing rollers 14 the trunnions 15 of which run in roller bearings 16 (Figure 4) supported in a bearing housing 17.

It will be noted that the drier cylinders are adapted to be frictionally driven from the main driving cylinders 2 through the friction flanges 6 thereby obviating the use of large driving gears and eliminating all delays in the operation of the machine usually encountered due to the breaking of gears and the time necessary for replacing the same.

Attention is directed to the fact that by equipping the drier cylinders with friction flanges the bearings and journal parts of the upper tier of drier cylinders are dispensed with, thus affording a machine of materially less parts and of a less expensive construction. It will also be noted that the arrangement of the friction flanges on the drier cylinders permits laying out of the cylinders in case the paper web tears and bunches up between the cylinders.

I am aware that many changes may be made and numerous details of construction may be varied through a wide range without departing from the principles of this invention, and I therefore do not purpose limiting the patent granted hereon otherwise than necessitated by the prior art.

I claim as my invention:—

1. The combination with a paper making machine drier unit, of a plurality of drier cylinders forming a part thereof, and friction mechanisms connected to drive said cylinders.

2. The combination with a paper making machine drier unit, of a plurality of drier cylinders, driving means connected to drive certain of said cylinders, and co-acting friction mechanisms on all of said cylinders to permit the cylinders to receive a drive from said driving means.

3. In a paper drier unit the combination with a plurality of co-acting drier cylinders, of means connected to drive one of said cylinders, and friction flanges on said cylinders adapted to co-act one with the other to cause the drive transmitted to said one cylinder to be imparted to the remaining cylinders.

4. In a paper drying machine drier unit a drier cylinder, a flange thereon, and friction means engaging said flange to rotate the cylinder.

5. In a paper drying machine drier unit, a drier cylinder, a ring flange rigidly secured to one end thereof, and means for frictionally engaging said flange to cause rotation of the cylinder.

6. In a paper drier unit, a main drier cylinder, means connected therewith for rotating the same, a flange mounted on said main drier cylinder, an auxiliary cylinder, and a flange thereon co-acting with the main cylinder flange to receive a drive therefrom.

7. In a paper drier unit a plurality of upper and lower drier cylinders positioned in staggered relation with the upper cylinders supported on the lower cylinders, roller bearings for supporting the lower cylinders, means for driving certain of said cylinders, and co-acting flanges on said cylinders to permit the drive to be transmitted from said selected cylinders to the remaining cylinders.

In testimony whereof I have hereunto subscribed my name.

EARL ELWIN BERRY.
